UNITED STATES PATENT OFFICE.

MILDRED C. SCHMOLZE, OF NEW YORK, N. Y., ASSIGNOR TO FRANKLIN SIMON & CO.,
OF NEW YORK, N. Y., A CORPORATION OF NEW YORK.

SLIP.

Application filed January 19, 1925. Serial No. 3,356.

To all whom it may concern:

Be it known that I, MILDRED C. SCHMOLZE, a citizen of the United States, and a resident of the city of New York, borough of Manhattan, in the county and State of New York, have invented a new and Improved Slip, of which the following is a full, clear, and exact description.

This invention relates to garments and particularly to what is known as a slip and has for an object to provide an improved construction wherein a neat fitting garment is presented with a minimum number of parts.

Another object of the invention is to provide a neat fitting slip wherein the parts are of simple construction capable of easy manufacture at a minimum cost.

A further object of the invention is to provide an improved slip wherein the upper part is fitted adjacent the waistline while the lower part is specially designed to be shad-owproof.

In the accompanying drawing—

Figure 1 is a perspective view of a slip embodying the invention, the same being shown on a figure.

Figure 2 is an enlarged fragmentary sectional view through Figure 1 on line 2—2.

Figure 3 is an enlarged inside elevation of one of the points where the garment is fitted.

Figure 4 is a sectional view through Figure 3 on line 4—4.

Figure 5 is a detail section illustrating the joint between the upper edge of the skirt portion and the lower end of the body portion.

In constructing the garment, the upper part 1 is made in tubular form from a flat substantially rectangular piece of goods and secured together by a suitable seam 2. The upper edge 3 is provided preferably with a suitable hem to which shoulder straps 4 and 5 are connected. In order to cause the upper part 1 to fit or conform somewhat to the figure of the person wearing the garment, restricted portions 6 and 7 are provided, the same being on diametrically opposite sides and preferably under the arms but spaced from the arms to a point near the waistline. In order to provide a desired fit, the restricted portions 6 and 7 are not cut and

seamed but are folded as shown in Figures 3 and 4 and the folds held in the desired position by a suitable line of stitching 8. In Figure 4 it will be seen that part of the material of the garment is folded back twice upon itself and the line of stitching 8 is extended through all of the folds but not to the outside surface 9 of the garment. It will also be noted that the line of stitching 8 is comparatively short and, consequently, four loose members 10 are formed which are in the nature of darts though they are as a matter of fact merely folds maintained substantially in the position shown in Figures 1 and 3 by the line of stitching 8. In Figure 3, the various dotted lines 11 indicate merely the approximate line of folding while the lines 12 and 13 indicate the opposite edges of the folds.

Connected to the upper part 1 is a lower part or what may be termed a skirt structure 14 which is made from a rectangular piece of goods folded at 15 upon itself and connected together at the upper edge by a line of stitching 16. The lower edge of the upper part 1 is connected to the upper edge of the skirt 14 by a line of stitching 17 and then the lower edge of the upper part 1 is folded over with a covering fold 18 and then folded back at 19, after which, a line of stitching 20 is applied which is seen from the outside of the garment and which extends through the folded end 19 and the skirt 14 as shown in Figure 2. Before stitching the skirt 14 in place, an inverted box plait or kick opening 21 is provided whereby a comparatively small skirt structure is presented ordinarily but one that may freely expand when walking as occasion may demand.

It will be noticed that the restricted portions at 6 and 7 are formed by means of a pleat on the inner side of the garment as shown in detail in Figure 4, produced by folding portions on opposite sides of an intermediate point and bringing the folded portions to one overlying the other at their meeting edges and stitching at 8 through the folded portions, but not through the outer surface of the body. This is well illustrated in Fig. 4 and shows a construction in which the restricted portion is produced in a simple manner and permanently and in such manner as to avoid any unseemly appear-

ance and without the necessity of any separate fastening devices other than the mere seam shown at 8.

What I claim is:

- 5 1. A slip having its upper part in tubular form and provided at the opposite sides thereof below its upper end and approximately at the waistline with constricted portions having spaced apart portions of the
- 10 garment folded inwardly and with the outer fold of one side overlapping the outer fold of the other side and with a line of stitches through all of the folds except the outer portion of the overlying fold said stitches
- 15 being sufficient in number to hold the parts together and present a seam appreciably shorter than the lengths of the respective folds whereby the constricted portions for producing fit are secured in a simple effec-

tive manner simply by folding and permanently securing the garment, as and for the purposes set forth.

2. A slip comprising an upper part and a lower or skirt part, the latter being folded at its lower edge into double form, a seam securing the folded portions of the skirt near the upper edge thereof, an upper or body portion overlapping at its lower end the upper end of the skirt and having a portion extending thence upwardly and over and down the inner side of the skirt for a short distance and then returned, stitches securing the return portion of the body to the skirt and separate stitching securing the body near its extreme lower edge to the skirt, the latter stitching being below the others specified as and for the purposes specified.

MILDRED C. SCHMOLZE.
